UNITED STATES PATENT OFFICE.

EPHRAIM S. JOHNSON, OF JERSEY CITY, NEW JERSEY.

DESIGN FOR A PENCIL-CASE.

Specification forming part of Design No. 6,229, dated October 29, 1872.

To all whom it may concern:

Be it known that I, EPHRAIM S. JOHNSON, of Jersey City, in the county of Hudson and State of New Jersey, have invented a Design for Pencil and Pen Cases, of which the following is a specification:

The nature of my design is fully represented in the accompanying drawing, to which reference is made.

A represents the body or cylinder portion of a pen or pencil case, which may be made of any form and of any of the well-known materials suitable for the purpose; and B the handle, and C the point, of the pen or pencil, as the case may be.

The essential feature of my design is the alternating circumferential and longitudinal sec-

tions of mother-of-pearl and gold or other suitable material capable of producing a pleasing contrast.

In the drawing, the sections marked *a* represent mother-of-pearl, and the sections marked *e* represent gold.

But I do not confine myself to two sections in the length of the case A, as a greater number of subdivisions may be employed without affecting the object of my design.

What I claim as my invention is—

A design for a pencil-case, substantially as herein described.

EPHRAIM S. JOHNSON.
